UNITED STATES PATENT OFFICE

162,698

PARKING METER CASING

James Teague, Chicago, Ill., assignor to Miller
Meters, Inc., Chicago, Ill., a corporation of
Illinois

Application October 7, 1950, Serial No. 12,481

Term of patent 14 years

(Cl. D52—3)

To all whom it may concern:

Be it known that I, James Teague, a citizen of the United States, and residing at Chicago and State of Illinois, have invented a new, original, and ornamental Design for a Parking Meter Casing, of which the following is a specification, reference being had to the accompanying drawing, forming part hereof, wherein—

Figure 1 is a front elevational view of a parking meter casing, showing my new design;

Fig. 2 is an elevational view looking toward one side thereof;

Fig. 3 is a top plan view thereof; and

Fig. 4 is a bottom plan view thereof.

I claim:

The ornamental design for a parking meter casing, as shown.

JAMES TEAGUE.
